UNITED STATES PATENT OFFICE.

CHARLES PFANSCHMIDT, OF CHICAGO, ILLINOIS, ASSIGNOR TO VIBRAS-SAGE COMPANY, A CORPORATION OF ILLINOIS.

MASSAGE-MACHINE.

SPECIFICATION forming part of Letters Patent No. 766,897, dated August 9, 1904.

Application filed March 10, 1904. Serial No. 197,434. (No model.)

To all whom it may concern:

Be it known that I, CHARLES PFANSCHMIDT, a citizen of the United States, residing at Chicago, in the county of Cook and State of Illinois, have invented certain new and useful improvements in Massage-Machines, of which the following is a specification.

In the art to which the present invention relates it is desirable to use a machine which is of such simple construction that there will be little or no danger of its getting out of order and which at the same time will be cheap to manufacture and will therefore enable its use under circumstances which would prohibit the use of a more complicated machine.

The objects of the present invention are to produce a machine combining in the greatest degree simplicity, durability, and perfection of operation and at the same time a varying degree of vibration, enabling a single machine to perform with but slight readjustment the work of several machines having different degrees of vibratory action.

The invention consists in the features of construction and combination of parts hereinafter described.

In the drawings illustrating the invention, Figure 1 is a longitudinal sectional view of the preferred form of device; Fig. 2, a view similar to Fig. 1, showing the parts differently adjusted; Fig. 3, a modified form of device; Fig. 4, a detail view showing a modified form of mounting; Fig. 5, a face view of the eccentric plate for imparting vibration, and Fig. 6 a view showing a modified form of a vibratory shaft.

The massage-machine of the present invention is constructed to have a handle A of any usual and well-known shape having therein a longitudinally-extending sleeve a, within which is located a rotary shaft B, which connects with a flexible shaft b of any usual and well-known character. At the end of the handle is a casing C, which may be secured to the handle by means of a screw c, as shown in Fig. 1, or may be screw-threaded onto the end of the handle, as shown in Fig. 4. As shown in Figs. 1 and 2, the end of the casing is closed by means of a closing-plug D, which is pro-

vided with a slit d in its end for the insertion of a screw-driver or other similar implement thereinto, and said head is adjustable into and out of the casing to regulate the bearings therein contained.

On the inner end of the rotary shaft is a flat plate or disk E, which is rigidly secured at right angles to the shaft and is provided on its inner or acting face with a series of holes e, having different degrees of eccentricity with respect to the axial center of the plate or disk, and between the inner face of the disk and the end of the handle within the casing is a bearing-washer e', which may be formed of metal, fiber, or other suitable material and which forms a bearing for the disk and allows of its smooth and easy rotation within the casing as the shaft is rotated. Immediately opposite the disk and in axial line therewith is a bearing-block F, formed of hardened steel, which block is set within the closing-plug and is provided on its inner or acting face with a rounded recess f. Between the disk and the bearing-block is an eccentrically-mounted shaft G, preferably formed of steel of circular shape and having in its outer end a recess g and in its inner end a recess g', and within the disk or plate is a stud g'', having an enlarged head g''', adapted to enter the recess in the inner end of the shaft G, and said stud may be either screw-threaded into one of the holes in the disk or plate or loosely fitted thereinto to allow of its rotation. The outer end of the shaft G is mounted by means of a ball-bearing g'', which enters the recesses in the end of the shaft and the bearing-block and pivots the shaft between the bearing-block and the rotatable disk or plate, and the closing-plug being adjustable enables the bearings to be tightened or loosened at will to allow for any wear on the bearings in use. It will be understood that the stud may be entered into any one of the several holes in the face of the disk, so that the amount of eccentricity of the shaft G can be varied by changing the location of the stud from one of the holes having a small degree of eccentricity to one having a larger degree of eccentricity, thereby changing the character of the vibratory motion imparted

to the eccentric shaft. When the shaft is so changed, it will be necessary to readjust the bearing for the outer end of the shaft, and such readjustment can be effected by turning 5 the screw-threaded closing-plug, thereby bringing it nearer to or farther from the rotatable disk or plate with which it coöperates.

Upon the shaft G and substantially at right angles thereto is mounted a vibratory shaft 10 H, which is provided at its end with a ring or collar h, encircling the eccentrically-mounted shaft and movable thereon, and, as shown in Fig. 3, the shaft H is provided with a hole on its interior having screw-threads h', which 15 hole extends through the vibratory shaft, and into the hole is screw-threaded a stem I, having on its outer end a massage member i, and the stem is of a length to be screw-threaded through the vibratory shaft to abut against 20 the eccentric shaft and lock the ring in place thereon.

In Fig. 5 is shown a different arrangement 25 in which a vibratory shaft I' is employed, which shaft is split throughout its entire extent and is provided on its exterior with screw-threads i', and on the split shaft is screw-threaded a locking-collar i'', which is adapted to be turned on the split vibratory shaft to bring the split members thereof together as the locking-screw is upwardly moved, thereby at the 30 same time locking the stem of the massage member within the vibratory shaft and locking the collar onto the eccentric shaft at the same operation.

35 In Fig. 3 in place of the adjustable closing-plug and ball-bearing therein is employed a closing plug or cap J, through which is screw-threaded a bearing-stud j, having a rounded end j'', which performs the function of the 40 ball-bearing hitherto described and mounts the eccentric shaft in the same manner. In the arrangement of Fig. 3 when it is necessary to change the adjustment of the bearings the same can be effected by moving the 45 screw-bearing plug inwardly or outwardly to change the adjustment and locking it by means of a lock-nut j''.

The vibratory shaft projects through a slot 50 or opening K in the casing, and said slot or opening may be reinforced by means of a plate or bar k on the side of the opening against which the friction is most likely to take place, since during the operation of the device the natural tendency of the vibratory 55 shaft will be to bear against one side of the opening more than the other. In place of the reinforcing bar or plate, however, the edges of the opening may be tempered or hardened to resist the friction above referred to.

60 In use when it is desired to impart a slight degree of vibration to the massage member the collar on the vibratory shaft is moved into the position shown in Fig. 1, in which it lies near the axial center of the eccentrically-mounted shaft, so that but a slight degree of

vibratory action is imparted thereto; but when it is desirable to increase the vibratory action the collar is moved into the position shown in Fig. 2, thereby throwing it farther from its axial center and increasing the vibratory action. When the least amount of vibratory action is desirable, the collar will be adjusted in the position shown in Fig. 1, and the bearing-stud on the rotatable disk will be inserted into the hole nearest to the center thereof, thereby reducing the vibratory action to a minimum, and when it is desirable to give the maximum vibratory action the bearing-stud will be inserted into the hole farthest from the center and the collar moved into the position shown in Fig. 2. In this manner a great variation of vibratory action can be had, and the parts are so arranged that the bearings may be adjusted to act perfectly under all circumstances.

When the parts are arranged to have the 85 minimum amount of vibration, the massage member will impart a rapid rubbing action, which tends to improve the circulation and renovate the cuticle at the point of application. When the parts are arranged to give a 90 moderate degree of vibration, a motion combining the rubbing action and a slight degree of pounding or kneading action will be imparted, which vibration will be of sufficient intensity to stimulate the circulation and 95 nerve action not only at the point of application but at a considerable distance therefrom, and when the parts are arranged to give the maximum amount of vibration a considerable 100 pounding and twisting movement will be imparted, which will be more apparent than the rubbing action hitherto described and will be of sufficient intensity to stimulate the nerve-centers and impart a vibration throughout a 105 wide radius, affecting parts of the body along 110 way removed from the point of immediate application. This difference in character of the vibration will greatly enhance the value 115 of the machine and increase its field of operation, and the character and degree of vibration can be regulated to meet the requirements of each particular case. It will thus be seen that the device is simple in construction, employing but few parts, which do not require any great degree of milling or other machine-work in their formation, and that when arranged as shown the wear and friction on the parts will be reduced to a minimum and that the parts are so arranged that they may be removed for repair or substitution without difficulty and without readjusting the remaining parts of the machine.

What I claim as new, and desire to secure by Letters Patent, is—

1. In a massage-machine, the combination 125 of a casing, a rotatable shaft, an eccentrically-mounted shaft within the casing actuated by the rotatable shaft, and a vibratable shaft slidably adjustable on the eccentrically-mounted shaft and adapted to be rigidly held thereon 130

at substantially right angles thereto, substantially as described.

2. In a massage-machine, the combination of a handle, a rotary shaft extending through the handle, a disk on the end of the rotary shaft, a stud entered into the disk at a distance from its axial center, an eccentrically-mounted shaft contacting with the stud at one end and actuated thereby, a pivotal mounting for the opposite end of said shaft, and a vibratory shaft carried by said shaft and adjustable thereon to vary the degree of vibration imparted to the vibratory shaft, substantially as described.

15 3. In a massage-machine, the combination of a handle, a casing on the end of the handle, a rotary shaft entered into the casing, a disk on the end of the rotary shaft provided with a series of holes in its face having different degrees of eccentricity with respect to the axial center of the disk, a stud adapted to enter the several holes in the disk, an eccentrically-mounted shaft having one end actuated by the stud, a pivotal mounting for the 25 opposite end of said shaft in line with the axial center of the disk, a vibratory shaft carried by the eccentrically-mounted shaft, and a massage member carried by the vibratory shaft, substantially as described.

30 4. In a massage-machine, the combination of a handle, a casing on the end of the handle, a rotary shaft extending longitudinally of the handle, a disk within the casing on the end of the rotary shaft, a stud entered into the disk, a closing-plug screw-threaded into the outer end of the casing, a recess in the closing-plug, and entered into the recess, an eccentrically-mounted shaft having recesses in its opposite ends for the reception of the 40 stud and the ball, a vibratory shaft set in angular relation to the eccentrically-mounted shaft and adjustable thereon, and a massage member carried by the vibratory shaft and adapted to have imparted thereto varying degrees of vibration, substantially as described.

45 5. In a massage-machine, the combination of a handle, a casing on the end of the handle, a rotary shaft extending longitudinally of the handle, a disk within the casing on the 50 end of the rotary shaft, a stud entered into the disk, a closing-plug screw-threaded into the outer end of the casing, a recess in the closing-plug, and entered into the recess, an eccentrically-mounted shaft having recesses in its opposite ends for the reception of the 55 stud and the ball, a vibratory shaft set in angular relation to the eccentrically-mounted shaft and adjustable thereon, a screw-threaded stem passing through the vibratory shaft 60 and adapted to be brought into contact with the eccentrically-mounted shaft, and a massage member carried by the screw-threaded stem, substantially as described.

6. In a massage-machine, the combination

of a handle having at its end a casing, a rotary 65 shaft having its end entered into the casing, a disk on the end of the rotary shaft and provided with a series of recesses of different eccentricity, a pivotal mounting adapted to be entered into any one of the recesses, an eccentric shaft having its inner end actuated by the pivotal mounting and having its outer end pivoted in a line with the axial center of the eccentric disk, and a massage member connected with the eccentrically-mounted shaft 75 and adapted to have vibration imparted thereto, substantially as described.

7. In a massage-machine, the combination of a handle having at its end a casing, a rotary 80 shaft having its end entered into the casing, a disk on the end of the rotary shaft and provided with a series of recesses of different eccentricity, a pivotal mounting adapted to be entered into any one of the recesses, a shaft having its inner end actuated by the pivotal 85 mounting and having its outer end pivoted in a line with the axial center of the disk, a vibrating shaft slidably and adjustably mounted on the shaft, and a massage member connected with the vibrating shaft and adapted 90 to have varying degrees of vibration imparted thereto by reason of the adjustment of the pivotal mounting for the eccentrically-mounted shaft and the adjustment of the vibrating shaft thereon; substantially as described. 95

8. In a massage-machine, the combination of a handle, a rotary shaft extending longitudinally of the handle, a casing on the end of the handle, an adjustable screw-threaded closing-plug entered into the end of the casing, a bearing-block on the inner face of the closing-plug, a rounded recess in the bearing-block, a disk on the end of the rotary shaft provided in its face with a series of recesses of different eccentricity with respect to the 105 axial center of the disk, a stud having a rounded outer end adapted to be entered into the recesses and entered into the recess in the bearing-block in line with the axial center of the disk, a shaft provided with recesses in its ends 110 adapted to bear against the ball and the stud and adapted to have different degrees of eccentric motion imparted thereto by the adjustment of the stud, a vibratory shaft outwardly extending therefrom and provided 115 with a collar encircling the eccentrically-mounted shaft adjustable thereon, and a massage member connected with the vibratory shaft and adapted to have different degrees of vibration imparted thereto by the adjustment 120 of the pivotal mounting for the eccentrically-mounted shaft and the position of the vibratory shaft thereon, substantially as described.
